Patented Apr. 6, 1926.

UNITED STATES PATENT OFFICE.

SETH N. JORDAN, OF BURLINGTON, IOWA.

DISCONNECTING SWITCH.

Application filed June 5, 1924. Serial No. 718,130.

To all whom it may concern:

Be it known that I, SETH N. JORDAN, a citizen of the United States, residing at Burlington, in the county of Des Moines and 5 State of Iowa, have invented certain new and useful Improvements in Disconnecting Switches; and I do declare the following to be a full, clear, and exact description of the invention, such as will enable others skilled 10 in the art to which it appertains to make and use the same.

My invention relates to new and useful improvements in the so-called disconnecting switches used in connection with high tension wiring, switches of this type being usually mounted at elevated points and being controlled by a pole having a hooked end. Numerous switches of this general character have heretofore been devised, but the 20 majority of them have been complicated and expensive and have included at least two insulators, and the construction has been such as to require at least two more insulators to take the strain of the wires from the 25 insulators of the switch. It is the object of the present invention however, to reduce the cost of manufacturing disconnecting switches, to the minimum, by materially simplifying their construction, making it 30 possible to use only one insulator for insulating switch parts and dead-ending the wires, the strain of the latter being exerted in a straight line at opposite ends of the insulator, so as to have no shearing 35 effect on the latter.

With the foregoing in view, the invention resides in the novel subject matter hereinafter described and claimed, the description being supplemented by the accompanying drawing.

Figure 1 is a side elevation partly broken away and in section, showing a disconnecting switch constructed in accordance with my invention.

Figure 2 is a sectional view on line 2-2 of Fig. 1, cut horizontally.

Figure 3 is a sectional view showing the one-piece insulator and associated parts.

Figure 4 is a vertical transverse sectional 50 view as indicated by line 4-4 of Fig. 1.

Figure 5 is a detail side elevation of the insulator, showing a different form of construction.

In the drawing above briefly described, 55 the numeral 1 designates a one-piece insulator formed of any desired material having

sufficient strength and insulating qualities, said insulator preferably having two, alined, oppositely projecting branches 2 and 3, and a central branch 4 at right angles to said 60 branches 2 and 3. In the preferred form of construction, a nut 5 is embedded in the branch 4 to receive the threaded end of an attaching bolt or the like 6, by means of which the insulator may be secured to a 65 cross arm or the like 7. I have shown a construction in which the nut 5 is threaded and cemented into the branch 4, as indicated at 8, but said nut could well be anchored in the insulator in any other desired 70 manner. In fact, other suitable provision could be made for attaching the insulator to a support, not necessitating the use of the nut 5.

A pair of elongated wire anchors 8 and 9 75 have been shown projecting oppositely from the branches 2 and 3 respectively, each of said anchors being preferably in the form of a short length of metal rod, the inner ends of the two rods being anchored in the 80 branches 2 and 3, for instance by threading and cementing them, as indicated at 10. The outer ends of the rods 8 and 9 have suitable provision, such as openings 11, for connecting the high tension current conducting wires thereto, and for dead-ending these 85 wires, prior to connecting them to the rods 8 and 9, the branches 2 and 3 may be provided with wire-receiving openings 2^a and 3^a.

Projecting laterally from the rod 8 at a point spaced outwardly from the insulator 1, I have shown a rigid metallic arm 12 to which a switch blade 13 is pivoted at 14, said blade being much longer than the insulator and projecting beyond both ends of the latter, the end portions of said blade being preferably parallel with the anchors 8 and 9 for the current conducting wires. The end of the blade 13, opposite the arm 12, is receivable between a pair of contacts 15 which are secured to and project laterally from the anchor 9, in outwardly spaced relation with the insulator. The free extremity of the blade 13 may well be formed with an opening 16 to receive a hook or the like on the end of an operating pole, so that the switch may be opened or closed whenever desired. Suitable stops 17 are preferably provided on the contacts 15, to limit the 100 closing movement of the switch.

In Fig. 5, an insulator 1^a is shown identi-

cal with the insulator 1, with the exceptions that it is provided with water-baffling fins 1^b. Obviously, if desired, these fins may be used in connection with the form of construction above described, and in some instances, the insulator may be made without the dead-ending openings 2^a and 3^a.

By providing the construction shown and described or a substantial equivalent thereof, it will be seen that a great simplification has been effected in the ordinary construction of disconnecting switches, yet that regardless of its extremely simple and inexpensive nature, the improved switch will be equally as efficient as those heretofore provided. Excellent results are obtainable from the details disclosed and they are therefore preferably followed, but within the scope of the invention as claimed, minor changes may be made.

I claim:

1. A disconnecting switch comprising a one-piece insulator having a pair of oppositely projecting branches, and a third branch at right angles to said pair of branches adapted to be attached to a support, straight alined metallic wire anchors anchored at one end in said branches respectively and projecting oppositely therefrom, the outer ends of said anchors having pro-

vision for connecting wires thereto, a switch blade adjacent said insulator and having its end portions parallel with said wire anchors, a rigid arm extending laterally from one of said anchors and pivoted to one end of said blade, and a fixed contact extending laterally from the other anchor for co-action with the other end of the blade.

2. A disconnecting switch comprising a one-piece insulator having a pair of oppositely projecting branches and a central branch projecting at right angles to said pair of branches, a nut embedded in said central branch to receive an attaching bolt, straight alined metallic wire anchors embedded at one end in and projecting from said alined branches respectively, the outer ends of said anchors having provision for connecting wires thereto, a switch blade adjacent said insulator and having its end portions parallel with said wire anchors, a rigid arm extending laterally from one of said anchors and pivoted to one end of said blade, and a fixed contact extending laterally from the other anchor for co-action with the other end of the blade.

In testimony whereof I have hereunto affixed my signature.

SETH N. JORDAN.
